By his Attorney,
Nelson M. Howard

UNITED STATES PATENT OFFICE.

JOHN V. CARON, OF HAVERHILL, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

APPARATUS FOR USE IN THE MANUFACTURE OF BOOTS AND SHOES.

1,271,665.

Specification of Letters Patent.

Patented July 9, 1918.

Application filed November 18, 1915. Serial No. 62,234.

To all whom it may concern:

Be it known that I, JOHN V. CARON, a citizen of the United States, residing at Haverhill, in the county of Essex and State 5 of Massachusetts, have invented certain Improvements in Apparatus for Use in the Manufacture of Boots and Shoes, of which the following description, in connection with the accompanying drawings, is a specification, like reference characters on the drawings 10 indicating like parts in the several figures.

This invention relates to apparatus for operating upon the heels of boots and shoes 15 and particularly to mechanism for trimming off the portion of a top lift which projects beyond the breast of a Louis heel.

In the manufacture of ladies' shoes having Louis heels, the heel proper is frequently 20 made of wood and covered, except as to the breast portion, with thin upper leather or with celluloid or other material of a color to correspond with the upper of the shoe. The breast portion of a wood heel is usually 25 covered by a flap split from the grain face of the portion of the sole which extends over the heel seat. This flap or skiving is turned down and cemented to the breast face of the wood heel to cover the breast and also the 30 edges of the material which is used to cover the remainder of the heel.

To the tread face of the heel thus formed is attached a leather top lift, the breast end 35 of which is subsequently trimmed off flush with the leather covered breast face of the heel.

The object of the present invention is to 40 provide a convenient and effective apparatus for trimming off the projecting end of the top lift flush with the heel breast.

A feature of the invention consists in the 45 combination of a cutting block, a knife supported for tipping movement about an axis extending longitudinally of the knife to allow the side face of the knife and the surface of the heel breast to be held in contact, and means for effecting relative movement of the knife and heel to cause the top lift to be trimmed in the plane of the breast. 50 As shown, the knife is adapted to pass transversely across the breast face of a heel above the top lift. Relative movement of the shoe and knife longitudinally of the shoe will

cause the rear face of the knife to contact with the breast and pressure of the knife 55 against the breast will cause the knife to tip about the axis extending longitudinally of the knife and preferably coincident with the knife edge. When the knife and block are moved relatively to effect the trimming 60 of the top lift the breast face of the heel will constitute a guide for the knife and the projecting portion of the top lift will be trimmed off in a plane which is a continuation 65 of the plane of the adjacent portion of the heel breast, that is, the top lift will be trimmed flush with the heel breast. The knife may, as shown, be mounted at one end for universal movement, and the universal mounting may comprise three axes, 70 one axis being substantially parallel with the intersection of the breast face with the surface of the block to allow tipping movement of the knife and to enable it to be pressed flat against the breast, a second 75 axis arranged at right angles to the first axis which second axis permits the knife to be operated to effect its cutting operation, and the third a vertical axis to provide for movement of the knife over different portions of the surface of the cutting block. Preferably the pivot about which the knife is operated in trimming the top lift may be 80 adjusted relatively to the cutting surface in the direction of the vertical axis of the knife 85 for the purpose of bringing the knife edge into parallelism with the cutting surface to insure that the projecting portion of the top lift will be cleanly severed.

In the drawings,

Figure 1 is a perspective view representing the apparatus in use in trimming the top lift of a Louis heel; and

Fig. 2 is a perspective view of a heel after 90 being trimmed with the apparatus.

The apparatus comprises a cutting block 2 of wood or other suitable material. At one side of the block or on a projecting portion thereof is arranged the mounting for the knife 4 which is operated by the handle 6. The mounting comprises a forked and threaded stud 8 which can turn in the block 2 and is threaded into a plate 10 preferably countersunk into the under face of the block 2 and held therein by screws 12. The stud 100 8 may be adjusted vertically by rotating it

in the plate 10 about a vertical axis so that the knife edge will be parallel with the surface of the block when the cut is finished. In the forked upper end of the stud 8 a link 14 is pivoted by a pin 16. The upper end of the link is forked and in the fork a knife is pivoted by a pin 18 which is arranged at right angles to the pin 16. The end of the knife, therefore, has universal 10 movement, being movable about three axes at right angles to each other. The cutting portion of the knife 4 is curved to conform to the usual contour of Louis heel breasts just above the top lift.

15 In the use of the apparatus the shoe to be treated is placed upon a convenient portion of the block 2 with the tread face of the heel in contact with the block. The handle 6 is then grasped by the operator and the knife is swung about the axis of the stud 8 until the side face of the knife engages the breast face of the heel above the top lift. The operator then holds the heel with one hand and with the 20 other presses the knife against the breast face of the heel. If the pressure of the knife is greater at one edge of the knife than at the other, the knife will tip about the axis 16 and will become parallel with the portion of the breast against which it is pressed. The operator now moves the knife toward the projecting breast portion of the top lift, the knife tipping about the axis 16 to follow the contour of the breast 25 and finally engaging the top lift and trimming off the projecting portion in a plane which is a continuation of the plane of the adjacent portion of the breast. The knife is so adjusted by means of the threaded stud 30 8 that when the cut is finished the knife edge coincides with the surface of the block and clean cutting of the top lift along the edge next the block is assured. The knife may be swung over different portions of the block about the axis 8 and thereby a 35 large part of the surface of the block may be utilized.

Having thus described my invention, what I claim as new and desire to secure by 50 United States Letters Patent is:—

1. In an apparatus for trimming the breast edge of the top lift of a shoe heel flush with the breast, the combination of a cutting block against which the tread 55 face of the top lift of the heel is held, a knife supported for free tipping movement about an axis extending longitudinally of the knife edge to allow the side face of the knife to be held in contact with the surface 60 of the heel breast, and means for effecting movement of the knife to trim the top lift.

2. In an apparatus for trimming the breast edge of a top lift flush with the breast of the remainder of a heel, the combination of a cutting block adapted to re- 65

ceive the tread face of a shoe and its attached heel, a knife arranged to extend under the shoe shank and mounted for tipping movement about an axis lying substantially in the surface of the breast of the heel standing on the block and substantially parallel with the tread face of the heel, and means for effecting relative movement of the knife and heel to trim the top lift flush with the breast. 75

3. In an apparatus for trimming the breast edge of the top lift of a heel attached to a shoe flush with the breast of the remainder of the heel, the combination of a support for the tread face of the top lift, 80 a knife adapted to extend transversely across the breast between the shoe shank and the top lift, a mounting for the knife permitting movement of the knife to maintain it substantially in the plane of the 85 breast, and means for effecting movement of the knife toward the tread face of the heel to trim the top lift.

4. In an apparatus for trimming the breast edge of the top lift of a heel attached 90 to a shoe, the combination of a cutting block to receive the tread face of the top lift and a knife pivotally mounted for tipping movement about an axis substantially parallel with the knife edge whereby the knife is 95 adapted to follow the contour of the breast as it is moved in a direction from the shank of the shoe toward the tread face of the heel to trim the top lift.

5. In an apparatus for trimming off the 100 projecting portion of the top lift of a heel attached to a shoe flush with the breast of the heel, the combination of a cutting block to receive and support the tread face of the heel, a knife adapted to extend transversely 105 of the heel between the shank of the shoe and the top lift, a mounting for the knife constructed and arranged to allow the knife to follow the contour of the heel breast whereby the breast face of the heel constitutes a guide for the knife, and means for 110 effecting operation of the knife to trim the top lift flush with the guiding face of the heel.

6. In an apparatus for trimming the 115 breast edge of a top lift flush with the breast of the remainder of a heel, the combination of a cutting block upon which a shoe with its heel attached may be stood to support the top lift for the action of the knife, a 120 knife arranged to extend beneath the shank of the shoe and mounted for tipping movement about an axis lying substantially in the surface of the breast and substantially parallel with the tread face of a heel standing on the block, and means for effecting movement of the knife toward the block to trim the top lift. 125

7. In an apparatus for trimming the breast edge of the top lift of a shoe heel, a 130

5 cutting block, a knife pivoted at one side of the block for movement toward and from the surface of the block, and a second pivot allowing the knife to be swung in a horizontal plane for use of the knife on different portions of the block.

8. An apparatus for trimming the breast portion of the top lift of a heel attached to a shoe flush with the remainder of the heel 10 breast, comprising a support for the tread face of the heel, a narrow knife adapted to extend laterally of the shoe between the shank of the shoe and the top lift to be breasted, the support and the knife being 15 relatively adjustable to permit adaptation of the plane of the knife to the pitch of the heel, and means for effecting relative movement of the shoe and knife to trim off the breast end of the top 20 lift.

9. An apparatus for trimming the breast portion of the top lift of a heel flush with the remainder of the heel breast, comprising a support for the tread face of the heel, a 25 knife arranged to extend laterally of the heel in juxtaposition to the breast of the heel, the support and knife being relatively adjustable to enable the plane in which the knife acts to correspond to the plane of the 30 portion of the heel breast adjacent to the top lift, and means for effecting relative movement of the shoe and knife to trim off the breast edge of the top lift.

10. An apparatus for trimming the breast portion of the top lift of a heel attached to a shoe flush with the remainder of the heel breast, comprising a support for the tread face of the heel, and a trimming knife constructed and arranged to effect the trimming 35 operation by a movement directed

from the shank of the shoe toward the tread face of the top lift.

11. In an apparatus for trimming the breast edge of the top lift of a shoe heel flush with the breast of the heel, the combination of a cutting block for engagement with the tread face of the top lift, a knife adapted to extend transversely across the heel and supported for free tipping movement about an axis extending longitudinally 45 of the knife edge, said knife being constructed and arranged relatively to a heel on the cutting block to cause the side face of the knife to lie against the surface of the heel breast upon tipping movement of 50 the knife toward the heel so as to cause the knife to be a continuation of the surface of the heel breast, and means for effecting relative movement of the cutting block and the knife. 55

12. In an apparatus for trimming the breast edge of the top lift of a Louis heel, attached to its shoe, the combination of a cutting block to receive and support the tread face of the top lift and a knife adapted to engage the heel breast between the shank of the shoe and the top lift, the knife being mounted for movement about an axis lying in the plane of the breast of the heel and substantially parallel with the 60 edge of the knife whereby pressure of the knife and heel relatively together will hold the side face of the knife in the plane of the heel breast and relative movement of the knife and block will trim the top lift 65 from the breast toward the tread face of the top lift flush with the breast. 70

In testimony whereof I have signed my name to this specification.

JOHN V. CARON.
